UNITED STATES PATENT OFFICE.

CHARLES E. DE LONG, OF HOT SPRINGS, ARKANSAS, ASSIGNOR TO REMINGTON ARMS COMPANY, OF ILION, NEW YORK, A CORPORATION OF NEW YORK.

SINGLE-TRIGGER MECHANISM FOR FIREARMS.

SPECIFICATION forming part of Letters Patent No. 690,243, dated December 31, 1901.

Application filed May 31, 1901. Serial No. 62,597. (No model.)

To all whom it may concern:

Be it known that I, CHARLES E. DE LONG, a citizen of the United States, residing at the city of Hot Springs, in the county of Garland, 5 State of Arkansas, have invented a certain new and useful Improvement in Single-Trigger Mechanism, of which the following is a full, clear, and exact description, such as will enable others skilled in the art to which it applies 10 to make and use the same, reference being had to the accompanying drawings, forming part of this specification, in which—

Figure 1 is a side elevational view of a portion of a gun provided with my improved 15 single-trigger mechanism. Fig. 2 is a sectional view on line 2 2, Fig. 1. Fig. 3 is a sectional view on line 3 3, Fig. 1. Fig. 4 is an elevational view as seen from the opposite side. Fig. 5 is a sectional view on line 5 5, 20 Fig. 4. Figs. 6, 7, and 8 are detail views showing the parts in different positions.

This invention relates to a new and useful improvement in single-trigger mechanism for guns having a plurality of barrels, one object 25 being to enable the operator to successively release or trip the firing mechanism by the manipulation of a single mechanism in the form of a trigger.

Another object of this invention is to provide 30 means to take care of what is known as the "involuntary" pull on the trigger, which frequently occurs immediately after the discharge of the shell or cartridge from one barrel when the operator manipulates the trigger with what is termed a "stiff finger" or does not immediately upon pulling the trigger relax the pressure of his finger on the same, which involuntary pull might result in firing 35 the second barrel in quick succession.

With these objects in view the invention 40 consists in the arrangement, construction, and combination of the several parts of my improved single-trigger mechanism, all as will hereinafter be more fully described and afterward pointed out in the claims.

In the drawings I have shown in Figs. 1, 2, 45 3, and 4 my improved single-trigger mechanism as applied to a well-known form of firing mechanism, which latter is illustrated solely 50 for the purpose of showing the application of

my device to a well-known construction; but it will be obvious to those skilled in the art to which my invention relates that the improved single-trigger mechanism hereinafter described can be applied to any form of firing 5 mechanism, and therefore I do not wish to be understood as limiting myself to the particular form of firing mechanism shown.

In the drawings, A indicates what is known as the "frame," B the barrels, C the lifter arranged in the fore extension of the frame, D the hammer, E the sear, F the mainspring, G the trigger-tumbler, H the thumb-piece, I the tang, and J the top lever, all of said parts being practically of the usual and well-known 65 construction of the firearm commonly called a "double-barrel hammerless shotgun."

The general construction and operation of a double-barrel hammerless shotgun are well understood, and a detailed description here 70 is hardly necessary, but for purposes of explanation may be briefly described as follows: The gun shown is of the breakdown type, and upon the release of the barrel-locking mechanism by the manipulation of the top lever J 75 the barrels swing on a pivot, (not shown,) which in addition to actuating the ejecting mechanism in general also sets in motion the cocking mechanism, of which the lifter C, co-operating with the forwardly-projecting end 80 of the hammer D, forms a part. When one or both barrels of the gun have been fired and it is desired to reload the gun, the top lever J is moved laterally, usually to the right, which movement unlocks the barrels, allowing 85 them to swing on their pivot-point and eject or extract the shells, as the case may be, after which new shells may be inserted in the barrels. This movement also cocks the hammers of the gun, and simultaneously with the 90 unlocking of the barrels the safety attachment is actuated, to which safety attachment is connected the thumb-piece H. This safety attachment is actuated by the barrel-locking bolt K, directly operated by the top lever J, 95 which bolt moves rearwardly when the lever is manipulated. A rocking lever L, suitably pivoted to a projection A, formed on or secured to the frame A, and whose lower end is provided with a transversely-disposed pin 100

l, is designed to coöperate with a projection on the trigger-tumbler and prevent its upward movement when the gun is in a safe position. A bar *M*, pivotally connected to the 5 upper end of the lever *L*, has its outer or free end directly in the path of movement of (and is designed to be struck by) the bolt *K*. The extreme upper end of this rocking lever *L* co-operates with two projections *l'* and *l''*, de- 10 pending from and secured to the thumb-piece *H*, for actuating the latter, the projection *l''* being provided with a laterally-disposed pin *l'''*, which coöperates with a leaf-spring *i*, mounted upon the tang *I*, the object of which 15 is to hold said thumb-piece in its extreme forward or rearward positions in order to prevent accidental movement of the same.

It will thus be seen from the above and from an inspection of Figs. 1, 2, and 3 of the drawings that when the barrels of the gun have been swung on their pivot in the opening movement the hammers will have been cocked and the gun brought to a safe position, and after the barrels have been closed and locked 20 in their position for firing the hammers will still remain cocked; but the locking-bolt *K* will have moved forwardly away from the free end of the bar *M*, so that when it is desired to fire the gun the thumb-piece *H* is moved 25 forwardly and through the instrumentality of the projections *l'* and *l''* moves the upper end of the lever *L* and the bar *M* forwardly and the lower end of said lever *L* and its carried pin rearwardly out of the path of movement 30 of the projection formed on the trigger-tumbler *G* and permit of the upper movement of the latter.

N indicates a "stepping sear-controller," as it might be termed, and *O* and *O'* springs 40 coöperating therewith. The trigger-tumbler *G* is provided with steps or notches for coöperating with the sear-controller *N*, as will hereinafter be described. With reference to this trigger-tumbler *G*, I will hereinafter refer to the same as the "primary" trigger-tumbler and its companion *G'* as the "secondary" tumbler.

The primary trigger-tumbler *G* is pivoted to a block or bearing *a'*, formed on the frame 50 *A* of the gun, and is designed to have its web portion move through a slot *a'''*, formed in said frame, the finger portion of said primary trigger-tumbler being located below said frame, as is usual. Formed in the upper edge 55 and near the rear end of the web portion of this primary trigger-tumbler *G* is a series of notches or steps, which I have numbered 1 and 2, and projecting rearwardly over the notch 2 is formed an overhanging projection 60 3, the purpose of which will be presently explained.

The stepping sear-controller *N*, which co-operates with the notches or steps in or on the primary trigger-tumbler just described, consists of a horizontal strip of metal *n*, provided 65 with a downwardly-extending portion *n'*, which is formed at its lower end with a for-

wardly-bent portion *n''*. *n'''* indicates a step or projection formed on the under side of the top member of this stepping sear-controller, 70 which when the stepping sear-controller is in its normal position cooperates with the bridge-post *a*. In order to hold and guide this stepping gear-controller in place in the performance of its work, I have made use of the 75 screw or bolt *P* employed in guns of this design to stiffen and tie together the frame of the gun and the tang, said screw *P* passing through the slot *n⁴* and being secured to the bridge *a*. 80

It will be observed from the drawings that the springs *O* and *O'*, which coöperate with the stepping sear-controller, are so located that their tension is exerted to force said stepping sear-controller forwardly and downwardly at all times.

While I have referred in the above to the "primary" trigger-tumbler only and its carried notches or steps, I will here state that there are two trigger-tumblers and that in the 90 construction illustrated I have omitted the finger projection on the second or left barrel trigger-tumbler, which I have termed the "secondary" 95 tumbler and which I will now designate as *G'*. The finger portion of this secondary trigger-tumbler *G'* can, if desired, be retained. When only one trigger-tumbler is provided with the finger portion, the barrel controlled by that trigger-tumbler will always be the first to be fired; but when both tumblers retain 100 their finger portions that trigger-tumbler which is first pulled will fire the barrel which it directly controls and then without removing the finger from that trigger-tumbler the other barrel can be fired by proper manipulation 105 of the same. This secondary trigger-tumbler *G'* is provided with notches or steps and the overhanging projection, precisely the same as the steps or notches 1 and 2 and the overhanging projection 3 of the primary trigger-tumbler *G*, and is preferably made with the same dies as is said trigger-tumbler *G*. When said notches and said overhanging projection of said secondary trigger-tumbler *G'* are referred 110 to hereinafter, they will be designated as 1^a 115 and 2^a and the overhanging projection as 3^a.

The construction and operation of the triggers, sears, and hammers of a gun of this type are so well known that I deem it unnecessary to give a detailed description of the 120 same here; but for the sake of clearness I will mention that the sears, both left and right, coöperate with the primary trigger-tumbler *G* and the secondary tumbler *G'*, respectively, in the same manner as they do 125 with the triggers in any double-trigger gun—to wit., the upward movement of the triggers or tumblers causes the operation of the sears and effects the tripping of the hammers.

I will now describe the operation of my 130 improved single-trigger mechanism. Figs. 1 and 4 represent the parts as they appear after the gun has been cocked and in a position ready to be fired, and in which it will be ob-

served that the primary trigger-tumbler is in its normal or lower position and the portion n of the stepping sear-controller is resting upon the bridge or projection a^4 and the shoulder n''' is resting against one side of said bridge a^4 , and thereby arrests forward longitudinal movement of said stepping sear-controller. The bent portion n'' is seated in the notches or steps 1 and 1^a of the primary trigger-tumbler G and secondary tumbler G' , respectively. When the primary trigger-tumbler G is pulled and moves upwardly, as shown in Fig. 6, the sear controlled by said trigger-tumbler will be actuated and release 15 the hammer and fire the shell in one barrel, (in this instance the right,) and simultaneously with this movement the stepping sear-controller will be forced upwardly until its shoulder n''' rises above the bridge a^4 , whereupon the spring O will be in readiness when the trigger descends, and the sear-controller descends under the pressure exerted by the spring O' until the shoulder n''' is arrested 20 on top of the bridge a^4 , and the bent portion n'' is disengaged from the recess 1 to exert its pressure to move the stepping sear-controller longitudinally and forwardly. The parts are now in the position shown in Fig. 7, it being understood that in the above-mentioned 25 movement the secondary tumbler G' remains undisturbed and that the bent portion n'' will be raised out of the step 1^a . When pressure on the trigger-tumbler G is relaxed and the same approaches its normal position, the stepping sear-controller will descend until the downward movement of the latter is arrested 30 by the contact of the under face of the shoulder n''' with the bridge a^4 , as above described; but at this stage the trigger-tumbler has not completed its full return movement, and in doing so the notch or step 1 of said trigger-tumbler moves away from the bent portion n'' and the spring O forces said stepping sear-controller in the proper direction to cause 35 the bent portion n'' to register with and become engaged by the recesses 2 and 2^a , respectively, of the trigger-tumblers G and G' . The first barrel of the gun has now been fired, and by the construction shown in the 40 accompanying drawings provision is made to take care of the involuntary pull due to the recoil of the gun.

The mechanism employed for taking care of the involuntary pull consists of an escapement movement connected to the stepping sear-controller for retarding its action after becoming disengaged from the primary trigger-tumbler and before engaging the secondary tumbler. As shown in Figs. 1 to 4, inclusive, the stepping sear-controller carries a pivoted drag-pawl n^5 , which co-operates with a ratchet-wheel p . This ratchet-wheel is mounted for the sake of convenience upon a shaft arranged in the projection a , its axis of rotation being coincident with that of the lever L , thus enabling the employment of a common pivot-shaft for this ratchet-wheel

and lever. Conjoined to the ratchet-wheel is the gear p' , which meshes with a pinion p'' , the shaft on said pinion carrying an escapement-wheel p''' . p^4 indicates a vibrating escapement drag-pawl, one end of which is preferably weighted, said drag-pawl co-operating with the escapement-wheel. A spring n^6 co-operates with the drag-pawl n^5 to hold 75 the same in an operative position with respect to its ratchet-wheel.

Referring now to Fig. 6, where the primary trigger-tumbler is raised, it will be observed that the drag-pawl n^5 has slightly advanced— 80 about the distance of one tooth of the wheel p . When the gun is fired, the recoil follows instantly after the explosion of the charge, and it is at this time that the involuntary pull occurs. However, it will be noticed that 85 the primary trigger-tumbler is elevated and the stepping sear-controller is still in engagement therewith. As the trigger is released the tumbler G descends and the step n''' rests on the bridge a^4 , causing the stepping sear-controller to be disengaged from the primary trigger-tumbler. The stepping sear-controller is now in a position to move forwardly 90 under the shoulders 3 and 3^a , under the action of its impelling-spring O , but is unable 95 to do so quickly by reason of the restraining influence exerted by the drag-pawl engaging the ratchet-wheel p . Through the instrumentality of the escapement-train the escapement-dog must be vibrated a sufficient number of times to permit the train to rotate to a position where the drag-pawl n^5 is released 100 from engagement with the teeth of the ratchet-wheel and permits the stepping sear-controller to seat itself home under the projections 3 and 3^a in its final movement, said 105 final movement being free from restraint on the part of the escapement-train. When in this position, (shown in Fig. 7,) the manipulation of the trigger will, through the primary trigger-tumbler, lift the stepping sear-controller, which will in turn by its engagement under the shoulder 3^a lift the secondary tumbler and fire the left barrel. When 110 the gun is broken for the purpose of reloading, the bolt K engages the bar M for the purposes hereinbefore described and also the forward end of the stepping sear-controller, restoring said stepping sear-controller to its 115 normal position, and in so doing resetting the drag-pawl n^5 , as shown.

q indicates a pivoted lever, carrying a projection or finger q' , which is designed to be thrown into and out of the path of the vibrating escapement-pawl. When this finger is in 125 the path of the vibrating escapement-pawl, as shown in Fig. 1, it will be obvious that said pawl cannot vibrate, and consequently the escapement-train will not operate. The stepping sear-controller will not be permitted 130 to move forward to the full limit of its movement, but will be held in what might be termed a "half-way" position by reason of the engagement of the drag-pawl n^5 with the

ratchet-wheel p . In this position (shown in Fig. 8) the right barrel alone can be fired, and when the trigger is released the stepping sear-controller moves forward slightly, but not under the shoulder 3^a , and consequently a successive pull on the trigger will elevate only the primary trigger-tumbler. When it is desired to fire both barrels successively by successive pulls of the trigger, the finger q' is moved out of the path of the vibrating escapement-pawl, so that the escapement-train can operate, as before described. The finger q' is only employed for saving the wear on the escapement-train in the event that it is desired to repeatedly fire one barrel—say the right.

It will be noticed that in the event of an involuntary pull immediately succeeding the discharge of the first load the elevation or partial elevation of the primary trigger-tumbler will prevent the extension n'' entering under the shoulder 3^a , as shown in Fig. 8. The trigger and its connected tumbler must be in a full forward position before the extension on the stepping sear-controller can engage the shoulder 3^a . This engagement depends upon the operation of the escapement-train, which can be so adjusted as to operate rapidly or slowly, as required. In practice I have found that the train should be adjusted so as to prevent the stepping sear-controller from engaging the secondary tumbler while there is any liability of the recoil from the first discharge to cause an involuntary pull and successively fire the second barrel regardless of the intention of the operator; but this adjustment of the train, while carrying the stepping sear-controller slowly over what might be termed an "inoperative" position, must not be such as to interfere with the firing of the second barrel at the will of the operator. So far as the construction and operation of the stepping sear-controller are concerned, it is similar to that shown and described in United States Letters Patent No. 670,100, granted to me March 19, 1901.

The retarding device which I use is yieldable, as distinguished from being positive in its operation, and operates upon the sear-controller while the latter is in continuous motion, and in these respects it differs from a sear-controlling device such as that shown in my said prior patent, where the sear-controller is positively arrested in its forward movement before it reaches the position for firing the second barrel. The sear-controller is not stopped by the retarding device, which would require an intermediate pull of the trigger to free the sear-controller; but rather the speed of its forward movement is reduced without being stopped. It will be observed, however, that in the preferred form of retarding device, such as has been described, it ceases to act just before the sear-controller arrives at the forward limit of its movement, so that the speed of the sear-controller is accelerated or

is unrestrained during the final portion of its forward movement.

The above construction by repeated practical tests has been found to respond to ordinary conditions, so far as taking care of the involuntary pull caused by the explosion of the charge first fired. There are, however, causes which operate independently of the trigger mechanism which might result in the discharge of the second barrel independently of the involuntary pull of the operator—as, for instance, in breaking the gun the forward end of the sear might but slightly engage the hammer, so that a shock or jar would release the hammer, or if the gun was fully broken to cock the hammers the shoulders on the hammers might be so worn as to render them extremely sensitive, and a slight shock or jar would cause them to explode. As a precautionary measure to avoid the firing of the second barrel I provide means for locking the sear of the firing mechanism for the second barrel against accidental displacement, which locking mechanism is under control of the stepping sear-controller and is operated to release the sear in the second firing mechanism only after the involuntary pull resulting from the first barrel has occurred and after the stepping sear-controller is in operative engagement with the secondary tumbler. This locking mechanism consists of a lever R , which is pivoted, preferably, in the upper forward edge of the bridge a^4 , the lower end of said lever being provided with a shouleder recess engaging the tail of the sear, which coöperates with the secondary tumbler. A spring r holds the lower end of this lever normally in engagement with the sear when said sear is in its normal or lowered position. The upper end of the lever is received in a recess or slot n^7 in the stepping sear-controller and is designed to be struck by the end wall of said recess or slot at the final forward movement of the stepping sear-controller just as the bent portion of said stepping sear-controller is entering the recess 2^a under the projection 3^a . The operation of this lock is as follows: Should the sear, with which the locking-lever R coöperates, be elevated, the breaking of the gun will first restore the stepping sear-controller, after which the hammers will be cocked and the tail of the sear depressed. In its depressed position it is located under the lower end of the locking-lever. Consequently it is impossible to operate the sear and fire the second barrel when the lower end of lever R is in this forward position. When the first barrel is fired, the sear-controller, as above described, moves forward, and just as the bent portion passes under the shoulder 3^a the rear wall of the recess or slot n^7 engages the upper end of the lever R , so as to disengage said locking-lever from the sear in the firing mechanism of the second barrel. The second barrel can now be fired, as before described. It will be obvious that instead of

having the locking-lever R coöperate with the sear said locking-lever can coöperate with the tumbler G', if the sear is a part thereof; but where the sear is separately movable I prefer to have the locking-lever act directly upon the sear.

I am aware that minor changes in the arrangement, construction, and combination of the several parts of my device can be made 10 and substituted for those herein shown and described without in the least departing from the nature and principle of my invention.

Having thus described my invention, what I claim, and desire to secure by Letters Patent, is—

1. In a single-trigger mechanism, the combination with a primary trigger-tumbler, of a secondary tumbler, a stepping sear-controller, and means for retarding without stopping 20 the movement of said stepping sear-controller after the same has become disengaged from the primary trigger-tumbler and before it engages the secondary tumbler; substantially as described.

2. In a single-trigger mechanism, the combination with a primary trigger-tumbler formed with a shoulder 1, of a secondary trigger-tumbler formed with a shoulder 1^a and recesses 2^a, and a shoulder 3^a, a stepping sear-controller coöperating with said tumblers, a spring for moving said stepping sear-controller, and an escapement-train connected to said stepping sear-controller; substantially as described.

3. In a single-trigger mechanism, the combination with a primary trigger-tumbler, of a secondary trigger-tumbler, a stepping sear-controller, a spring for moving said sear-controller when disengaged from the primary 40 trigger-tumbler, into engagement with the secondary tumbler, and mechanism for retarding the sear-controller while in continuous movement; substantially as described.

4. In a single-trigger mechanism, the combination with the primary trigger-tumbler, of a secondary tumbler, a stepping sear-controller, a spring for moving the latter, a drag-pawl pivotally mounted on said stepping sear-controller, and an escapement-train including 50 a ratchet-wheel which coöperates with said drag-pawl; substantially as described.

5. In a single-trigger mechanism, the combination with the primary trigger-tumbler, of the secondary tumbler, a stepping sear-controller coöperating therewith, a spring coöperating with said stepping sear-controller, a drag-pawl carried by said sear-controller, an escapement-train including a ratchet-wheel which coöperates with said drag-pawl and 60 means arranged to free the drag-pawl from the teeth of the ratchet before the sear-controller completes its forward movement; substantially as described.

6. In a single-trigger mechanism, the combination with a plurality of firing mechanisms, including hammers and sears, of tumblers coöperating with the respective sears, a

stepping sear-controller coöperating with said tumblers, means for retarding the forward movement of the sear-controller arranged to 70 act while the controller is moving forward, without stopping the controller; and a barrel-locking mechanism for resetting the sear-controller; substantially as described.

7. In a single-trigger mechanism, the combination with a plurality of firing mechanism, including hammers and sears, of tumblers coöperating with said sears, a stepping sear-controller coöperating with said tumblers, an escapement mechanism, a drag-pawl carried by the sear-controller for engaging the escapement mechanism, a spring coöperating with the sear-controller for moving the same forwardly and operating the escapement mechanism, and a barrel-locking mechanism 80 for resetting the sear-controller and storing energy in the spring which actuates the same and the escapement-train; substantially as described.

8. In a double-barrel, breakdown gun, the 90 combination with the hammers, sears, top lever and slideable bolt K, of a primary trigger-tumbler for coöperating with one hammer and sear, a secondary tumbler for coöperating with the other hammer and sear, said primary 95 trigger-tumbler and said secondary tumbler being each provided with a series of notches or steps, an independently-operable stepping sear-controller for coöperating with said notches in said primary trigger-tumbler and 100 said secondary tumbler and connecting said tumblers together when said stepping sear-controller is in certain positions a spring for forcing said stepping sear-controller forwardly when the same is released by the proper manipulation of the primary trigger-tumbler in the performance of its work, the free or outer end of said stepping sear-controller being located directly in the path of movement of, and designed to be struck by, 110 the bolt K in its rearward movement, when the top lever is properly manipulated to unlock the barrels of the gun, and means for controlling the speed of movement of the stepping sear-controller after it is released 115 by the primary trigger-tumbler, and before it engages the secondary tumbler; substantially as described.

9. In a single-trigger mechanism, the combination with the tumblers and stepping sear-controller, of an escapement-train for controlling the movement of said stepping sear-controller, said escapement-train including a vibrating pawl, and a lever carrying a projection designed to be placed into or out of the path of said vibrating pawl; substantially as described.

10. In a single-trigger mechanism, the combination with a primary trigger-tumbler, of a secondary trigger-tumbler, sears coöperating 130 with said tumblers, a stepping sear-controller, and a lock for said secondary tumbler which is operated by said sear-controller; substantially as described.

11. In a single-trigger mechanism, the combination with primary and secondary tumblers and their sears, of a stepping sear-controller, and a locking-lever coöperating with the sear of the secondary tumbler, said locking-lever being operated by the sear-controller; substantially as described. 55
12. In a single-trigger mechanism, the combination with a trigger, of tumblers operated thereby, a stepping sear-controller, means for retarding the movement of said stepping sear-controller after passing out of engagement with one tumbler and into engagement with the other, and mechanism for locking said last-mentioned tumbler, said locking mechanism being operated to release said tumbler when the stepping sear-controller is completing its movement; substantially as described. 60
13. In a single-trigger mechanism, the combination with the primary trigger-tumbler, of a secondary tumbler, a stepping sear-controller, a spring-pressed locking-lever R for coöperating with the sear of the secondary tumbler, and a shoulder on the stepping sear-controller for engaging the locking-lever when the stepping sear-controller is completing its forward movement; substantially as described. 65
14. In a single-trigger mechanism, the combination with a primary trigger-tumbler, of a secondary tumbler, a stepping sear-controller, means for retarding the movement of said stepping sear-controller after the same has become disengaged from the primary trigger-tumbler and before it engages the secondary tumbler, and a lock for the sear controlled by the secondary tumbler, said lock being operated by the stepping sear-controller; substantially as described. 70
15. In a single-trigger mechanism, the combination with a primary trigger-tumbler, of a secondary trigger-tumbler, a stepping sear-controller, a spring for moving said sear-controller when disengaged from the primary trigger-tumbler into engagement with the secondary tumbler, mechanism for retarding said movement, a spring-pressed locking-lever coöperating with the sear of the secondary tumbler, and a shoulder on the stepping sear-controller for engaging said locking-lever when the sear-controller is completing its final movement and disengaging said lever from said sear; substantially as described. 75
16. In a single-trigger gun the combination of a trigger, two sears, a sear-controller arranged to move after the first barrel has been fired to a position to permit the firing of the remaining barrel, and a yielding retarding device acting upon the sear-controller, substantially as set forth. 80
17. In a single-trigger gun the combination of a trigger, two sears, a sear-controller arranged to be released when the first barrel is fired and to move to a position to permit the firing of the second barrel, and a retarding device arranged to act upon the sear-controller after it has been released and while continuously moving to a position to permit the firing of the second barrel, substantially as set forth. 85
18. In a single-trigger gun the combination of a trigger, two sears, a sear-controller arranged to be released when the first barrel is fired and to move to a position to permit the firing of the second barrel, a spring for moving the sear-controller, a retarding device connected with the sear-controller and arranged to reduce, without stopping, the speed of its movement and means for disconnecting the controller from the retarding device before it has completed its movement, substantially as set forth. 90
19. In a single-trigger gun, the combination of the trigger, the sears, a sear-controller arranged to be released when the first barrel is fired and to be moved to a position to permit the firing of the second barrel, and means, acting upon the sear-controller, arranged to reduce the speed of its movement during the first part of its forward movement and to accelerate its speed during the latter portion of such movement. 95
20. In a single-trigger-gun lock mechanism, the combination of a pair of sears, a trigger, a sear-controller arranged to be released when the first barrel is fired and to move to a position to permit the firing of the second barrel, and a lock for the sear of the barrel last to be fired and arranged to be operated by the sear-controller. 100

In testimony whereof I hereunto affix my signature, in the presence of two witnesses, this 29th day of May, 1901.

CHARLES E. DE LONG.
